UNITED STATES PATENT OFFICE

116,357

DESIGN FOR A LAMP SHADE

Joseph M. Angeletti, New York, N. Y.

Application April 20, 1939, Serial No. 84,409

Term of patent 3½ years

To all whom it may concern:

Be it known that I, Joseph M. Angeletti, a subject of the King of Italy and a resident of New York, in the county of New York and State of New York, have invented a new, original, and ornamental Design for a Lamp Shade, of which the following is a specification, reference being had to the accompanying drawing, forming part thereof.

In the drawing:

Fig. 1 is a view in side elevation of a lamp shade embodying my new design, and

Fig. 2 is a top plan view thereof.

The design is characterized by annular corrugations arranged in axially arcuate contour with the smallest of the corrugations at the middle of the shade, and said corrugations are convex exteriorly and concave interiorly of the shade.

I claim:

The ornamental design for a lamp shade, as shown and described.

JOSEPH M. ANGELETTI.
